ABSTRACT OF THE DISCLOSURE

A double-lever tool for cutting open containers of sheet metal or plastic sheet material having a pair of levers pivotally connected at one end, the levers at said one end formed with a pair of projecting tongues. A spring at the one end of the levers holds the other ends of the levers apart. A knife blade is carried on a first one of the levers. A fixed jaw and spring biased movable jaw is carried on the other lever. The jaws engage a bead at the top of a container while the knife cuts open the top of the container at the bead. The knife blade is mounted in the plane of the first lever or perpendicular to the first lever to cut the side wall or top wall respectively of the container.

The present invention relates to a double-lever tool for cutting open containers of sheet metal or plastic material with a bead projecting near the rims of the opening to be made.

By the word "containers" all types of containers are meant having mutually perpendicular top and side walls joined together with a peripheral bead extending around the joint between the walls.

For opening such containers, bell-crank tools are known (German patent specification 1,098,388). They have the disadvantage that they must be engaged several times (at least 5 times) and taken off again for cutting off a lid. As compared with this, the double-lever tool according to the invention runs automatically along the rim of the container when operated after one single engagement until the container is cut open by 360°.

This advantage is obtained with the double-lever tool according to the invention. The levers are spread by spring load and are manually pressed together for cutting. A knife blade is fastened on one lever of the tool while the other lever has clamping jaws engaging opposite sides of the bead during the cutting operation.

When the tool is mounted in a plane parallel to the container lid and the levers are pressed together, the clamping jaws close and grip the bead. A part of the lid is thereby cut from the container. Then clamping jaws open and the lever carrying them is guided along the bead into a new clamping position by the spreading spring.

When the levers are pressed together again, the clamping jaws first engage the bead, and then the knife blade is pulled toward the jaws. The knife blade may be fixed on the one lever parallel to the axis of the one lever. In this case the knife blade engages the side wall of the container and cuts the lid with the bead. The knife may instead be perpendicular to the axis of the lever carrying the knife blade, and in this case it cuts out the lid from the bead.

The clamping include a pin fixed on the second lever and a third lever pivotable on the second lever. The third lever has a jaw at one end formed with a pointed part and with an L-shaped part. The pointed part is urged toward the pin by a coil spring engaged on the pivot of third lever and having opposite ends engaged on the sec-

2

ond and third levers. The third lever is manually turned against spring bias to separate the pointed part of the movable jaw and the fixed jaw or pin so that the bead of the container can enter between them. When the third lever is released, the pointed part engages the outer side of the bead while the fixed jaw engages the inner side of the bead. Then the first and second levers can be pressed together while the jaws remain in place and the knife blade is drawn toward the jaws. When the first and second levers are released, these levers separate under spring bias while the knife blade remains in place and the third lever is automatically turned so that the shaped part of the movable jaw slide along the bead along with the fixed jaw. At the end of travel of the movable jaw, spring bias on the third lever turns this lever so that the pointed part of the movable jaw again engages the bead.

The drawing shows diagrammatically and partially in section two preferred embodiments of the invention.

FIG. 1 is a bottom plan view of the double-lever tool of the invention.

FIG. 2 is a top plan view on the tool according to the invention shown opening an oval can.

FIG. 3 is a longitudinal section through the knife leg of another embodiment of the double-lever tool of the invention.

The two levers 2 and 4 of the double-lever tool are spread according to this drawing by a volute spring 13 surrounding the pivot 15. In the shown embodiment, the levers carry jaws 16 and 17 so that the tool can also be used as a pair of tongs. On the lever 4, the knife blade 3 or 3' is fastened. It lies either parallel to the leg 4 or normal to it. A fixed clamping jaw is represented in the drawing by the pin 5 on lever 2. A pivotable jaw which coacts with pin 5 includes a double-armed lever 6 on bolt 12 which is fastened on the other lever 2. The lever 6 is pressed against the stop 19 by a volute spring 14 arranged around the bolt 12. The clamping jaws 5, 6, only open, if there is a force acting in the direction of the arrow 20. The head 10 of the container 7, 8 is inserted into the tool as shown in FIG. 3. The knife 3' cuts open the side wall of the container underneath the bead 10.

In the embodiment according to FIG. 1 the knife 3 cuts open the container lid 8 within the bead 10. In both cases (FIG. 1 and FIG. 3) the tool is held in a position overlaying the top wall 8 of the container 7, 8 as shown in FIG. 2.

Initially bead 10 is inserted between jaws 5 and 6. When the levers 2 and 4 of the tool are pressed together in the direction of the arrow 21 against the effect of the spring 13, the pointed part of jaw 6 frictionally engages bead 10 which is then clamped between this pointed part and the clamping jaw or pin 5, while the knife blade 3' or 3 respectively is forced into the container and cuts open the side wall of container 7 or the lid 8 respectively over the full length of the spreading angle of the levers 2, 4 of the tool. If now the compressed levers are released they can spread open again under the effect of the spring 13. Lever 4 stops while the lever 2 runs downward on the bead 10 (FIG. 2 of the drawing). The clamping jaws 5 and 6 release the bead 10 for this purpose as the force acting in the direction of the arrow 20 opens the clamping jaws 5, 6 against the effect of the spring 14. The tool thus travels along the full rim of the container through 360° and opens the container by mere continuous pressing together and letting it spread again.

What is claimed is:

1. A tool for cutting open a container made of sheet material, said container having mutually perpendicular top and side walls joined together, and a peripheral bead extending around the joint between the top and side

walls, said tool comprising in combination: first and second levers; a first pivot pivotally joining the levers together at one end thereof; a first coiled spring engaged on said pivot with opposite ends of said spring engaging the levers at said one end thereof and urging the levers apart to define a V-shaped configuration; a cutting blade on the first lever for cutting one of said walls adjacent to the bead; a pin defining a first fixed jaw on the second lever for engaging inside said bead above said top wall; a third lever; a second pivot pivotally securing the third lever to the second lever with one end of the third lever disposed near said first jaw; said one end of the third lever being formed with an L-shaped part and a pointed part spaced slightly apart and defining a second jaw; and a second coiled spring engaged on the second pivot and tending to urge said pointed part toward said first jaw, whereby the third lever can be turned manually against bias in said second spring to move the pointed part away from said first jaw to define a space into which the bead can enter when said one end of the first and second levers overlays the top of the container, whereby the bead will be gripped between the first jaw and said pointed part of the second jaw under spring bias when the third lever is released, and whereby the blade will cut one wall of the container when the other end of the first lever is pressed toward the other end of the second lever, and whereby the third lever will pivot against bias in the second spring so that the L-shaped part of the

5 second jaw contacts the bead and slides along the bead with the first jaw while the other end of the second lever moves away from the other end of the first lever, and while the blade remains engaged in said one wall when pressure on the first lever is released, whereupon the bead will again be engaged between the first jaw and pointed part of the second jaw at the end of movement of the other end of the second lever.

10 2. A tool as defined in claim 1, wherein said blade is disposed in a plane parallel to the first lever to cut the side wall of the container.

15 3. A tool as defined in claim 1, wherein the blade is disposed in a plane perpendicular to the first lever to cut the top wall of the container.
